UNITED STATES PATENT OFFICE

PAUL E. KLOPSTEG, OF CHICAGO, ILLINOIS, ASSIGNOR TO CENTRAL SCIENTIFIC COMPANY, OF CHICAGO, ILLINOIS, A CORPORATION OF ILLINOIS

ROTOR PROPELLED APPARATUS

Application filed May 11, 1929. Serial No. 362,346.

The principal object of this invention is to provide apparatus in which the basic features of the so-called Flettner rotor ship will be represented, and will, in operation, demonstrate the application of forces by which such a ship is propelled.

In the drawings—

Fig. 1 is a side elevation of the preferred embodiment of the apparatus, parts of the 10 track being broken away;

Fig. 2 is a plan view of the apparatus shown in Fig. 1; and

Fig. 3 is a transverse sectional view taken on the line 3—3 of Fig. 1.

Generally speaking, the apparatus 15 includes a car propelled by a rotor along a level track until arrested by buffers.

The frame 10 of the car is a channel shaped aluminum casting with the flanges 20 11 turned downwardly. It is mounted upon three wheels 12, each fixed to an axle 13, journaled in pivot bearings 14, carried by the flanges 11. The front and rear wheels are on one side and the intermediate wheel 25 on the other.

Rising from the front and rear of the web 15 of the car frame 10 is a mast, or pillar 16, made of brass tubing threaded externally at 17 to receive nuts 18 by which 30 it is clamped to the web 15.

The upper ends of the pillars are connected by a cross arm 19 secured in place by screws 20 threaded into the upper ends of the pillars. The cross piece 19 and the 35 web 15 are provided with pivot bearings 21 for the shaft 22 of the rotor 23. The shaft is made of steel with the end sockets hardened to cooperate with the pivot bearings. The rotor 23 is composed of a length 40 of brass tubing soldered at its ends to circular disks 24 which, in turn, are soldered to the shaft 22. The surface of the rotor is roughened in any suitable manner, as by means of a knurling tool, or broach.

The upper end of the shaft 22 is provided 45 with a thumb wheel 25 between which and the upper disk 24 there is a short drum section 26 upon which a cord 27 may be wound after being made fast to a pin 28.

The track comprises a channel bar 29 with

the flanges 29^a turned up, and their edges milled to a suitable curvature. Front and rear wheels are milled to slightly greater curvature so as to provide for a line contact between the wheels and the track.

About one-quarter the length of the bar from each end there is fitted a base casting 30 having lateral arms 31 equipped with leveling screws 32 by which the track can be accurately leveled.

A frame 33 rises from each end of the beam 29 and is equipped with buffers comprising pairs of phosphor bronze springs 34 lying close together except at their free ends where they are spread apart, substantially as indicated at 35, to facilitate the entry of a bar 36 extending across each end of the car frame 10, and projecting slightly beyond its sides, as best seen in Fig. 2.

When it is desired to make a demonstration the apparatus is set up substantially as illustrated in the drawings, the car is held against movement, and the cord 27 given a vigorous pull, spinning the rotor after the manner of a top, and it has sufficient properties of a fly-wheel to continue in rapid rotation for a suitable period.

A blast of air is then delivered against the rotor; for example, as by placing a fan in the position shown at 37, in Fig. 2. Assuming that the rotor is spinning in a counter clockwise direction, it will be apparent that, due to the roughened surface, a considerable amount of air will be carried around with it. Hence, the velocity of the air particles 85 are greater at A than at B and the pressure at B will, therefore, be greater than at A, and the car will be propelled to the left in Fig. 2.

This specific description and illustration have been used for the purpose of disclosure only and it is realized that the substance of the invention may be embodied in other forms, all of which are intended to be 95 covered by the appended claims.

For the best results in demonstration the axis of the rotor should be at right angles to the direction the vehicle is to be propelled, and the blast of air should have a 100

component normal to the axis of rotation.

I claim as my invention:

1. In apparatus of the class described, a car, a pair of posts rising from the car, a cross arm between the tops of the posts, an upper pivot bearing on the cross arm, a lower pivot bearing on the car, and an upright rotor rotatably mounted between the bearings.
  2. In apparatus of the class described, a track, a car on the track, an upright rotor, a rigid self supporting frame mounted on the car for supporting the rotor, and a friction buffer to limit the travel of the car.
  3. In apparatus of the class described, a track, a car on the track, an upright rotor rotatably mounted on the car, a friction buffer at each end of the track, and means carried by the car engageable with the buffer to limit the travel of the car.
  4. In apparatus of the class described, a track, means for leveling the track, a friction buffer at each end thereof, a car adapted to run on the track, a rigid self supporting frame rising from the car, an upright rotor journalled in the frame, and means on the car cooperating with the buffer to bring the car to a stop without shock.
- 30 In testimony whereof I affix my signature:

PAUL E. KLOPSTEG.
